UNITED STATES PATENT OFFICE.

TREVOR RANDALL GAUTIER, OF NASHUA, NEW HAMPSHIRE, ASSIGNOR TO NASHUA GUMMED & COATED PAPER COMPANY, OF NASHUA, NEW HAMPSHIRE, A CORPORATION OF MASSACHUSETTS.

STRIP-SERVING MACHINE.

Application filed June 7, 1923. Serial No. 643,907.

To all whom it may concern:

Be it known that I, TREVOR R. GAUTIER, a citizen of the United States, and a resident of Nashua, in the county of Hillsborough and State of New Hampshire, have invented an Improvement in Strip-Serving Machines, of which the following description, in connection with the accompanying drawings, is a specification, like characters on the drawings representing like parts.

This invention relates to strip serving machines, and particularly to machines for serving strips of adhesive gummed tape for immediate application by the operator to a package, box or the like.

In order that the principle of the invention may be readily understood, I have disclosed a single embodiment thereof in the accompanying drawings, wherein—

20 Fig. 1 is a side elevation of a strip serving machine embodying my invention;

Fig. 2 is a plan view thereof;

Fig. 3 is an underneath plan view of a cover for a part of the machine;

25 Fig. 4 is a detail in vertical section taken through the strip roll support and adjacent portion of the frame or housing;

Fig. 5 is a plan view of the forward end of the machine, the cover of Fig. 3 being removed;

Fig. 6 is a vertical cross section upon the line 6—6 of Fig. 5;

Fig. 7 is a vertical longitudinal section taken through the forward part of the machine, the cover being removed;

Fig. 8 is a plan view of the reservoir and its parts removed from the machine;

Fig. 9 is a front transverse section upon the line 9—9 of Fig. 8;

40 Fig. 10 is an inside plan view of a gear carried by the shaft of the moistener roll;

Fig. 11 is a detail in vertical section through one of the side walls of the frame or housing and adjacent parts; and

45 Fig. 12 is a rear elevation of the upper part of the reservoir.

My invention, one type or embodiment of which is herein disclosed, constitutes an improvement upon the strip serving machines shown in the United States patent to Mortimer, No. 1,384,082, July 12, 1921, and the patent to Emmert, No. 1,442,058, January 16, 1923. This application contains among

its claims the broad claims for subject matter common to it and to my related copending application, Serial No. 714,592, filed May 20, 1924, which latter likewise pertains to strip serving machines of the general type above mentioned, and which discloses and claims certain further improvements thereon and on the mechanism shown and described herein.

The machine of my invention is, as stated, intended to feed, cut, moisten and deliver strips of tape in adhesive condition to an operator for immediate manual application by him to the package to be sealed. Such machines are well known in the art. They are intended for rough general use, and in stores are in almost constant use. It is therefore highly important that the construction of the machine be such as to prevent breakage or disarrangement of parts necessitating delay or interruption in the use thereof. An important object of my invention, therefore, is to improve the general structure of such a machine in a number of ways having such end in view.

As the preferred embodiment of the invention, I have disclosed a machine of the general type shown in the said patents, but obviously my invention as to certain features at least may be used in other types of strip serving machine. The features herein disclosed are, however, peculiarly adapted for use in connection with a mechanism of the disclosed type.

Referring more particularly to the drawings, the frame or housing of the machine is represented at 1 in the several figures, it having opposite side castings which are suitably connected at bottom and rear as by tie members 2 shown in Fig. 7, in which are secured screws 3 and at the front by means hereinafter described. The housing is preferably provided with feet 4, which are rubber shod, as shown at 5. Within the rear portion of the frame or housing between the side walls thereof is received a roll 6 of desirably previously gummed paper tape, although my invention may be applied in certain aspects thereof to machines wherein an ungummed strip is fed from a roll past a suitable gum or adhesive applying device. Desirably, however, the strip is previously 100 gummed and is fed past the moistener.

The strip may be of any suitable width, and it is important that one edge of the strip should be in a fixed relation or alignment with the corresponding end of the feed roll. Therefore, as shown most clearly in Figs. 2 and 4, I have provided means for holding the strip roll 6 against the inner face of the left hand wall looking toward the rear of the machine. In order to provide means for this purpose which will readily permit the insertion or removal of the strip package or the substitution of a wider or narrower package, I preferably provide a holding means herein consisting of a circular disk or plate 7 carried by a spindle 8 extending through an opening 9 in a hub 10 in the wall of the housing. Said spindle 8 is longitudinally grooved as indicated at 11 to a sufficient depth to receive a spring 12 desirably bent as shown, and having its end 13 inserted in a socket 14 in the spindle. The construction is such that the spring 12 presses outward against the inner wall of the hub 10 with sufficient force to hold the plate or disk 7 in any position to which it is adjusted, thereby holding the roll or package firmly against the opposite wall of the housing, but permitting the paper to be fed by the feeding means readily and yet with sufficient friction or tension.

The feeding means may be of the general type shown in the said patents to Mortimer and Emmert, and to that end I provide a hand operated or feed lever 15, shown most clearly in Fig. 1, as pivoted at 16 upon a lateral hub or projection from the housing, it being provided with a strong coil spring 17 tending constantly to move said hand operated lever upwardly. Said lever is provided with a projection 18 to permit ready manual operation. The forward end of the lever is guided in its downward movement in a slotted member 19, the slot being of sufficient length to permit full movement of the lever, and thereby a feeding of a sufficient length of the strip. Any suitable means may be provided for limiting the length of strip to be fed and severed. I have herein represented for the purpose the said guide 19 as having a plurality of downwardly inclined, open-ended notches 20, 20, in any one of which may be readily positioned a looped member 21, the lower end of which in any position underlies the edge 22 of the lever 15, 18, and thereby limits the downward movement thereof. The lever 15 is provided with an internal, curved rack 23, which meshes with a pinion 24 upon the end of the shaft 25 of the feed roll 26. The construction is desirably such as to permit slight downward movement of the movable severing blade before the feeding of the strip commences, thereby to bring said blade below the feeding plane of the strip. To this end, means may be employed

substantially as shown in either of the said patents.

The feed roll 26 may be of any suitable size and is preferably formed as a drum or hollow metallic member which at its end 70 opposite the lever 15, 18 is provided with a gear 27 (Fig. 6) fast thereon or formed therewith. The said gear is intended to rotate the lower moistener roll 28, which is carried in a suitable reservoir 29. Inasmuch as for the best construction the reservoir 29 should be removable from the machine, it is evident that means should be provided permitting such removal of the reservoir with the least disassembling of the parts and particularly without disarrangement of gearing. To that end, I provide an intermediate gear 30 which meshes with and is driven by the gear 27 on the feed drum or roll. The said gear 30 is loosely supported on a very short hub or stud formed with or secured to the inner face of that side wall of the frame or housing. For the purpose I have represented a stud 31 having an inner head and held in place by an axially positioned screw. In order to prevent said gear 30 from falling from position if and when the reservoir 29 is removed, I have provided an annular flange 32 carried by the feed drum or roll 26 just inside the gear 27 of said roll or drum, and in such relation to the parts that at all times it prevents the intermediate gear 30 from being removed or falling from place. Said flange also acts as a guide for the edge of the paper at that side of the machine, and therefore serves a double purpose.

The moistener roll 28 may be of any suitable material, but desirably it is of some suitable porous material, such as disclosed in the said Mortimer patent. It is provided with a sleeve 33 itself receiving a shaft 34 which at its end, herein the end nearest the feed lever 15, is received in a socket 35 tightly secured in place or formed in the wall of the reservoir 29 and in such way in either case as absolutely to prevent escape of water through that wall of the reservoir. A great difficulty heretofore has been experienced through the escape of water from the reservoir along the shaft of the moistener. The water seeps through the smallest opening and acting upon the outer face of the reservoir tends to cause corrosion thereof. I have devised means wholly preventing the escape of water from the reservoir yet permitting the positive rotation of the moistener roll 28. For this purpose I provide the shaft 34 with keys or feathers 36 which engage suitable notches in the end of the hub or sleeve 33, and I integrally form upon or weld or otherwise suitably secure to the end of the shaft 34 a gear 37 shown also in Fig. 10. Said gear upon its inner face has an annular groove 38 within which is re-

ceived a suitable packing 39 contacting with the outer face 40 of the reservoir wall, and in such a way as wholly to prevent the escape of water from the reservoir.

5 Difficulty has been found in providing a reservoir that will contain a moistener roll of sufficiently large size and yet will hold a sufficient supply of water to last for a substantial length of time. Obviously if the 10 moistener roll be of sufficient size to extend nearly to the bottom of the reservoir, there is little free space for the reception of water. I have met this difficulty by providing a supplemental roll or member 41 of some 15 suitable material, such as cork, said member being desirably of substantially the length of the moistener roll 28. Said roll 41 is provided with means to hold it yieldingly against said moistener roll 28, and for this 20 purpose I have herein provided a supporting frame having a spring portion to hold said roll 41 against the moistener. For this purpose, I have provided the frame shown most clearly in Fig. 7. The frame, which is indicated generally at 42, is of general rectangular, skeleton form, but is bent into a general V shape, as indicated in Fig. 7, the lower portions of the frame being springy and serving to hold the roll 41 against a 25 moistener. I have provided simple means for holding the frame securely and yet detachably in place. For this purpose, I have provided an elongated clip member 43 which upon its inner face is provided with desirably two downwardly extending clips or members 44 to engage the flat face 45 of the frame 42. The said clip 43 at its rear, as shown most clearly in Fig. 12, is provided with a plurality of and desirably three depending portions 46, some at least of which 30 may have projections 47 temporarily to engage corresponding slight depression upon the outer rear wall of the reservoir 29, thus holding the clip member 43 firmly in position yet permitting it to be removed, and 35 therefore permitting the frame 42 with its roll 41 to be readily removed. It is obvious that such construction is a simple one which can be cheaply manufactured and yet one 40 which provides a thoroughly efficient means for securing the desired operation of parts.

The reservoir is provided with an opening 49 which may be of any suitable character. Desirably the front wall of the reservoir 50 supports at its upper edge a clip member 50 which is generally similar to the clip member 43, it being provided with outer depending clips 51 and similar inner clips 52 between which is received the upper edge 53 of the front wall of the moistener. At a suitable point upon its inner edge said clip member 50 is formed with a projection 54 constituting a stripper. Said stripper engages a suitable peripheral groove 55 upon the moistener roll, thereby preventing the

forward edge of the feeding strip from being carried down the surface of the moistener roll 28 as the latter rotates.

The reservoir 29 is provided with lateral guides or flanges 56, 57 shown most clearly in Fig. 9, and which are received upon inner flanges upon the inner faces of the side walls of the frame or housing. One of such flanges is clearly shown at 58 in Fig. 6. In order to hold the reservoir in position, and yet in such a way as to permit the ready removal thereof, I have herein provided a rod 59 which is threaded at one end as indicated at 60 for reception in the threaded socket 61 in a side wall of the frame or housing. The said pin is provided with a head 60' by which it may be readily turned. Said pin passes through an aligned opening 61' in the opposite wall of the frame or housing and also through openings 62, 63 at the top of the side walls of the reservoir near the front thereof. By rotating pin 59, the side walls at their forward end may if desired, be sufficiently sprung or drawn together to engage frictionally the side walls of the reservoir and thereby assist in maintaining the same in position.

The strip severing means is desirably of the type employing a fixed blade and a movable blade pivoted to cooperate therewith. Blades of the same general type are shown in the said patents, but the means herein disclosed constitutes a marked improvement thereon. Difficulty has heretofore occurred in the prolonged or continued use of strip severing means of the general type herein disclosed, through constant heavy impact of the spring-impelled, hand-operated lever, such as 15, with the movable member or blade of the severing device. Where the initial shock of impact is taken by the movable blade, being brought against a stop, not only is said blade injured, but it becomes displaced or sufficiently loosened, so that it does not effectively cooperate with the fixed blade. I have provided means whereby the initial impact is not taken by the movable blade nor initially by a stop for said blade, and I have further provided means whereby the impact of the severing stroke of the blade is cushioned.

The fixed member of the severing device is represented most clearly in Figs. 5 and 6 as a stationary blade 64 held in position by screws 65, 65 securing said blade against laterally flanged portions of the side walls of the housing. The lower edge of said blade is sufficiently sharpened and at the right hand thereof viewing Fig. 6, there is provided a pivotal pin 66 whereon is suitably mounted the movable blade 67. A coiled spring 68 which surrounds said pin and is secured to the fixed blade 64 at 69 and at its opposite end 70 takes over the upper edge of the blade 67, tends to move the

movable blade 67 downward at all times. Therefore immediately upon initial downward movement of the operating lever 15, 18, the movable blade 67 starts downward.

As shown most clearly in Fig. 1, the side wall of the frame or housing nearest the operating lever 15 is provided with an integral lug or abutment 71 positioned in the path of the lever 15 and so located that 10 in the upward movement of said lever, the latter first strikes the under edge of the movable blade 67, thereby moving said blade upward, but before said blade is itself stopped or before it comes into engagement with 15 any cushioning means, the upper edge of the operating lever 15 at 72 engages the under face of the lug 71. Thus the heavy or initial shock of movement of the lever is received directly by the housing of the machine and 20 is absorbed thereby without injury to the parts.

The upward movement of the movable blade 67 which has been imposed or initiated by the rapid upward movement of the 25 lever 15, causes said movable blade to continue upward after the edge 72 of the lever 15 has contacted with the stop or abutment 71, and the upper edge 73 of said movable blade then contacts with the lower end 74 of a pin 30 75 extending downward from the under side of a preferably metallic strip 76 which, as shown most clearly in Figs. 5 and 7, is secured by screws 77, 78 to the upper faces of spaced lugs 79, 80, in which one side 35 wall of the frame or housing upwardly terminates. The strip 76 is of sufficient width and is relatively narrow, so that it is very slightly springy, and thus the relatively slight or reduced impact of the 40 severing blade 67 is readily absorbed by the pin 75 and its supporting strip 76.

The side wall of the frame or housing opposite the lugs 79, 80 is provided with corresponding lug-like terminals 79', 80', 45 and upon these is secured a preferably metallic strip 82 similar to the strip 76. In the lugs 79, 80 are provided lateral openings constituting bearings or supports for a roll 83 desirably metallic and preferably 50 circumferentially grooved at spaced points, as indicated at 84 in Fig. 5. Said roll 83 acts to hold the severed strip down upon the moistener roll 28. Said roll 83 is desirably vertically yielding, and for that purpose the openings in the said lugs 79, 80 are desirably sufficiently enlarged as indicated in Fig. 7. In addition, springs, one of which is indicated at 85, may be provided in the vertical sockets extending down to 55 said enlarged openings or bearings, and below said springs may be positioned the removable plugs or pins 86 if desired.

Similarly I may and desirably do provide above the feed roll or drum 26 a co- 60 operating feed roll 87 which is desirably

metallic and desirably circumferentially grooved as indicated at 88 in Fig. 5. The said roll 87 has fast therewith a pinion 89 which directly meshes with the gear 27 upon the relatively large moistener roll. 70 Said pinion 89, it will be observed, is outside of or beyond the annular ring or flange 32.

In order to guide the strip from its initial position as a roll or package 6, I provide 75 any suitable means. Desirably I provide a thin, springy, skeleton-like metal strip 90, shown most clearly in Figs. 2 and 7. It is bent at substantially right angles as indicated at 91, where it rests upon a transverse pin 92 secured in the side walls of the frame or housing, and in such way that the forward, substantially vertical part 93 of said strip depends between the feed roll 26 and the movable severing blade 67. The 80 horizontal portion of the metallic strip 90 is bent so that it overlies the feed roll 26 as indicated at 94, and the lower end 95 of said strip underlies the bottom 96 of the part of the housing wherein the roll 90 or package 6 is received.

The said feed roll 26, as most clearly shown in Fig. 2, is circumferentially grooved, as indicated at 97 in Fig. 2, and the spaced, longitudinally extending parts 98 of the skeleton-like strip 90 are received in said grooves wherein they are sufficiently depressed to permit the surface of the feeding tape or paper to rest upon the exposed portion 99 of the feed roll 26, and therefore 100 to be fed by reason of such contact. The ring like portions 100 between the grooves 88 of the upper roll 87 contact with the upper surface of the tape or paper, and thereby effect the feeding movement thereof. 105

Further to guide the feeding tape or paper, I may and desirably do provide two thin, springy, metallic strips 101, 102 respectively secured by screws 77, 103 and 78, 104 to the longitudinally extending metallic strips 76, 82. Each of said strips is of the bent form shown and each may be and desirably is slotted to provide lower fingers 105, 106. 110

Overlying the part of the framing having the lugs 79, 80, 79', 80', I provide a removable cover 107, shown in Figs. 1, 2, 3, 6. It is desirably a relatively heavy metal piece extending the full width of the machine, and at one side it has a relatively long lateral projection 108 overlying the pivoted end of the movable severing blade and at its other side it has a shorter lateral extension 109 overlying the opposite end of the fixed blade 64. Desirably I provide means for securing said cover in position, but in such a way that it can be readily removed, and yet the securing means is not so positioned or so constructed as to be readily broken. For this purpose I desir- 115 120 125 130

ably provide a spring 110, shown most clearly in Figs. 3 and 6 as secured to a downwardly projecting lug 111 upon the under face of the cover. The said spring

5 110 is shaped as shown, so that its free, slightly yielding end 112 will, when the cover is pushed downward into shape, ride under the longitudinally extending strip 76. Thus, the cover is held in position, but in 10 such a way that it can be removed by a relatively slight application of upward pressure.

Having thus described one illustrative embodiment of my invention, I desire it to 15 be understood that although specific terms are employed, they are used in a generic and descriptive sense and not for purposes of limitation, the scope of the invention being set forth in the following claims.

20 Claims:

1. In a machine for serving strips of adhesive tape, a frame or housing having opposite side walls providing a space between them for supporting a package of 25 tape in position to be drawn upon by the feeding means, one of said side walls constituting a lateral support for the tape package, a thin disk-like member constituting the opposite lateral support for the 30 tape package, said disk-like member having a spindle extending through an opening in the adjacent side wall, said spindle having a spring adapted to engage the wall of the 35 opening and to sustain the disk-like member and its spindle in any position of lengthwise adjustment of said spindle, whereby any width of package or tape receivable between the said side walls may be supported in proper position for feeding.

40 2. In a machine for serving strips of adhesive tape, a frame or housing having opposite side walls providing a space between them for supporting a package of tape in position to be drawn upon by the feeding means, one of said side walls constituting a lateral support for the tape package, a thin, disk-like member constituting the opposite lateral support for the 45 tape package, said disk-like member having a spindle extending through an opening in the adjacent side wall, said spindle having a lengthwise slot, a spring secured in said slot and shaped to engage the surface of the 50 opening in the side wall with sufficient friction to hold said disk and its spindle in any position of lengthwise adjustment of said 55 spindle, and whereby any width package of tape receivable between the said side walls may be supported in proper position for feeding.

60 3. In a machine for serving strips of adhesive tape, a frame or housing having opposite side walls and with provisions for supporting a package of tape, tape feeding means including a rotatable member having

a gear at one end thereof, a reservoir supported for ready withdrawal between the sides of the frame or housing, a rotatable moistener supported in said reservoir and removable therewith as a unit, a gear fast 70 with said moistener and removable with said reservoir, an intermediate gear mounted for rotation upon the inner face of one side wall of the housing and adapted to mesh with both said previously mentioned gears, and 75 means for supporting said intermediate gear in operative position between the side walls when the reservoir with its moistener and gear are withdrawn.

4. In a machine for serving strips of adhesive tape, a frame or housing having opposite side walls and with provisions for supporting a package of tape, tape feeding means including a rotatable member having a gear at one end thereof, a reservoir 80 supported for ready withdrawal between the sides of the frame or housing, a rotatable moistener supported in said reservoir and removable therewith as a unit, a gear fast 85 with said moistener and removable with said reservoir, and an intermediate gear mounted for rotation upon the inner face of one side wall of the housing and adapted to mesh with both said previously mentioned gears, said rotatable member having a flange 90 adjacent its gear and adapted to extend sufficiently past said intermediate gear to support the same in position when the reservoir with its moistener and gear are withdrawn.

5. In a machine for serving strips of adhesive tape, a frame or housing having opposite side walls and with provisions for supporting a package of tape, tape feeding means and tape severing means, said severing means including a fixed blade and a movable blade mounted for opening movement downward from the service path of the strip or tape, an operating member for the severing blade adapted to impact therewith, and thereby to move the same upwardly into strip severing relation with the fixed blade, and an abutment upon the frame or housing against which said operating member is adapted to impact before the movable severing blade reaches the end of its movement, thereby absorbing shock from said operating member and preventing said movable blade from itself receiving the full shock of operating movement.

6. In a machine for serving strips of adhesive tape, a frame or housing having opposite side walls and with provisions for supporting a package of tape, tape feeding means and tape severing means, said severing means including a fixed blade and a movable blade mounted for opening movement downward from the service path of the strip or tape, an operating member for the severing blade adapted to impact there-

- with, and thereby to move the same upwardly into strip severing relation with the fixed blade, an abutment upon the frame or housing to receive impact of the operating member in its upward movement, and a stop or abutment for the severing blade in its impelled upward movement, positioned to receive contact of the blade after contact between the operating member and its said abutment.

7. In a machine for serving strips of adhesive tape, a frame or housing having opposite side walls and with provisions for supporting a package of tape, tape feeding means and tape severing means, said severing means including a fixed blade and a movable blade mounted for opening movement downward from the service path of the strip or tape, an operating member for the severing blade adapted to impact therewith, and thereby to move the same upwardly into strip severing relation with the fixed blade, and a lug or abutment upon the side wall of the frame or housing positioned to be engaged by the edge of the operating member that engages the movable severing blade, so located as to be engaged by said operating member before the upward movement of the severing blade is completed.

8. In a machine for serving strips of adhesive tape, a frame or housing having opposite side walls and with provisions for supporting a package of tape, tape feeding means and tape severing means, said severing means including a fixed blade and a movable blade mounted for opening movement downward from the service path of the strip or tape, an operating member for the severing blade adapted to impact therewith, and thereby to move the same upwardly into strip severing relation with the fixed blade, a lug or abutment upon the side wall of the frame or housing positioned to be engaged by the edge of the operating member that engages the movable severing blade, so located as to be engaged by said operating member before the upward movement of the severing blade is completed, and cushioning means above the severing blade and positioned to be engaged thereby subsequent to the engagement of said operating member with said lug or abutment.

9. In a machine for serving strips of adhesive tape, a frame or housing having opposite side walls and with provisions for supporting a package of tape, tape feeding means and tape severing means, said severing means including a fixed blade and a movable blade mounted for opening movement downward from the service path of the strip or tape, a pivoted, upwardly spring-actuated, operating member for the severing blade adapted to impact therewith and thereby to move the same upwardly into strip severing relation with the fixed

blade, a lug or abutment upon the side wall of the frame or housing positioned to be engaged by the edge of the operating member that engages the movable severing blade, so located as to be engaged by said operating member before the upward movement of the severing blade is completed.

10. In a machine for serving strips of adhesive tape, a frame or housing having opposite side walls and with provisions for supporting a package of tape, tape feeding means and tape severing means, said severing means including a fixed blade and a movable blade mounted for opening movement downward from the service path of the strip or tape, a pivoted, upwardly spring-actuated, operating member for the severing blade adapted to impact therewith and thereby to move the same upwardly into strip severing relation with the fixed blade, a lug or abutment upon the side wall of the frame or housing positioned to be engaged by the edge of the operating member that engages the movable severing blade, so located as to be engaged by said operating member before the upward movement of the severing blade is completed, and cushioning means above the severing blade and positioned to be engaged thereby subsequent to the engagement of said operating member with said lug or abutment.

11. In a machine for severing strips of adhesive tape, a frame or housing having opposite side walls and with provisions for supporting a package of tape, rotatable tape feeding means and tape severing means, said severing means including a fixed blade and a movable blade mounted for opening movement downward from the service path of the strip or tape, an operating member for the severing blade having means for operating said feeding means in one direction of movement and adapted to move the severing means upwardly into strip severing relation with the fixed blade, a lug or abutment upon the side wall of the frame or housing positioned to be engaged by the edge of the operating member that engages the movable severing blade, so located as to be engaged by said operating member before the upward movement of the severing blade is completed.

12. In a machine for severing strips of adhesive tape, a frame or housing having opposite side walls and with provisions for supporting a package of tape, rotatable tape feeding means and tape severing means, said severing means including a fixed blade and a movable blade mounted for opening movement downward from the service path of the strip or tape, an operating member for the severing blade having means for operating said feeding means in one direction of movement and adapted to move the severing means upwardly into strip severing relation

with the fixed blade, a lug or abutment upon the side wall of the frame or housing positioned to be engaged by the edge of the operating member that engages the movable

5 severing blade, so located as to be engaged by said operating member before the upward movement of the severing blade is completed, and cushioning means above the severing blade and positioned to be engaged 10 thereby subsequent to the engagement of said operating member with said lug or abutment.

13. In a machine for serving strips of adhesive tape, a frame or housing having opposite side walls between which the package or roll of tape may be positioned for feeding movement, a reservoir adapted to be positioned between said side walls and having moistening means, said reservoir and said 15 side walls having openings which are aligned transversely of the machine when the reservoir is positioned, and a securing pin 59 adapted to be passed through said openings and having means for engagement with one 20 of them, whereby the reservoir is held in position between the side walls of said frame or housing.

14. In a machine for serving strips of adhesive tape, a frame or housing having opposite side walls providing a bottomed chamber between them for supporting a package of tape in position to be drawn upon, feeding means for the tape, means to operate the feeding means for the tape including a rotatable member, operating means for said rotatable member, and a readily removable guiding strip of resilient material for the tape from said chamber, with means for supporting the same to extend over the rotatable member of the feeding means and beneath and resiliently to bear against the bottom of the chamber for the tape package.

15. In a machine for serving strips of adhesive tape, a frame or housing having opposite side walls providing a chamber between them for supporting a package of tape in position to be drawn upon, feeding means including a pair of feed rolls, at least one of which is provided with circumferential grooves, and a resilient guiding strip longitudinally slotted to provide spaced members adapted to lie in the grooves of said feed roll but permitting the tape to contact with the feed roll between said members, said guiding strip being prolonged so as to extend continuously from said feed roll and along the path of the tape to the package-receiving chamber and having its rear end supported thereat whereby the feeding end of the tape is continuously guided from its initial position in said chamber to said feed roll to insure its proper engagement with the latter.

16. In a machine for serving strips of ad-

hesive tape, a frame or housing having opposite side walls providing a chamber between them for supporting a package of tape in position to be drawn upon, feeding means including a pair of feed rolls, at least one of which is provided with circumferential grooves, a resilient, readily removable guiding strip longitudinally slotted to provide spaced members adapted to lie in the grooves of said feed roll but permitting the tape to contact with the feed roll between said members, said strip extending to and resiliently engaging and being supported for ready removal by an overhanging wall of the tape package receiving chamber, and severing means in advance of the feeding means.

17. In a machine for serving strips of adhesive tape, a frame or housing having opposite side walls providing a space between them for supporting a package of tape and positioned to be drawn upon, strip feeding and severing means in advance of said supported tape package, and a cover having a spring member secured to its under side and adapted yieldingly to engage the frame or housing so as to hold the cover in position.

18. In a machine for serving strips of adhesive tape, a frame or housing having opposite side walls providing a space between them for supporting a package of tape in position to be drawn upon, a reservoir adapted to be received and supported between said side walls, a rotatable moistener in said reservoir, moisture feeding means for said moistener in said reservoir below the moistener and having a surface movable with said moistener, and spring means carrying said moisture feeding means and itself supported by the reservoir.

19. In a machine for serving strips of adhesive tape, a frame or housing having opposite side walls providing a space between them for supporting a package of tape in position to be drawn upon, a reservoir adapted to be received and supported between said side walls, a rotatable moistener in said reservoir, moisture feeding means in said reservoir below the moistener, a yielding frame supporting said moisture feeding means, and means detachably to connect said frame to a wall of said reservoir.

20. In a machine for serving strips of adhesive tape, a frame or housing having opposite side walls providing a space between them for supporting a package of tape in position to be drawn upon, a reservoir adapted to be received and supported between said side walls, a rotatable moistener in said reservoir, said moistener having a shaft extending through a lateral wall of the reservoir, a gear upon the outer end of said shaft, means for rotating said gear, said gear having packing adapted to engage the

outer face of the reservoir about the opening in the side wall thereof, thereby preventing escape of moisture from the reservoir.

21. In a machine for serving strips of adhesive tape, a frame or housing having upright side walls providing a space between them for supporting a package of tape in position to be drawn upon by the feeding means, one of said side walls constituting a lateral support for the tape package, a thin disk-like member constituting the opposite lateral support for the tape package, said disk-like member having fast therewith a spindle extending through an opening in the adjacent side wall and longitudinally movable therein to selected position with its attached disk-like member for supporting the tape package between said disk-like member and the opposite wall of the frame or housing.

22. In a machine for serving strips of adhesive tape, a frame or housing having opposite side walls and with provisions for supporting a package of tape, tape feeding means and tape severing means, said severing means including a fixed blade and a movable blade mounted for opening movement away from the service path of the strip or tape, an operating member for the severing blade adapted to impact therewith, and thereby move the same into strip severing relation with the fixed blade, and an abutment upon the frame or housing against which said operating member is adapted to impact before the movable severing blade reaches the end of its movement, thereby absorbing the shock from said operating member and preventing said movable blade from itself receiving the full shock of operating movement.

23. In a machine for serving strips of adhesive tape, a frame having provisions for supporting the package of tape, tape feeding means and tape severing means, said severing means including a fixed blade and a movable blade mounted for opening movement away from the service path of the strip or tape, an operating member for the severing blade adapted to impact therewith, and thereby move the same into strip severing relation with the fixed blade, and an abutment upon the frame or housing against which said operating member is adapted to impact before the movable severing blade reaches the end of its movement, thereby absorbing the shock from said operating member and preventing said movable blade from itself receiving the full shock of operating movement.

24. In a machine for serving strips of adhesive tape, a frame or housing having opposite side walls between which the package or roll of tape may be positioned for feeding movement, a reservoir adapted to be positioned between said side walls and hav-

ing moistening means and securing means to engage the side walls of the reservoir and the side walls of the frame or housing.

25. In a machine for serving strips of adhesive tape, a frame or housing having opposite side walls between which the package or roll of tape may be positioned for feeding movement, a reservoir adapted to be positioned between said side walls and having moistening means, and means for springing together the side walls of the reservoir and the corresponding walls of the frame or housing so as detachably to hold the reservoir in position within the frame or housing.

26. In a machine for serving strips of adhesive tape, a frame or housing having opposite side walls providing a place between them for supporting a package of tape in position to be drawn upon, a reservoir adapted to be received and supported between said side walls, a rotatable moistener in said reservoir, said moistener having a shaft extending through a lateral wall of the reservoir, a gear fast upon the outer end of said shaft, and means for rotating said gear and moistener, said gear having an annular groove and a packing in said groove to engage the adjacent stationary outer face of the reservoir, thereby effectively preventing escape of moisture from the reservoir.

27. In a machine for serving strips of adhesive tape, a frame or housing having opposite side walls providing a space between them for supporting a package of tape in position to be drawn upon, a reservoir adapted to be received and supported between said side walls, a rotatable moistener in said reservoir, said moistener having a sleeve provided at one end with a notch, a shaft loosely mounted in said sleeve and extending through a lateral wall of said reservoir, said shaft having a key thereon removably to engage said notch, a gear fast upon the outer end of said shaft outside the reservoir, means for rotating said gear, and means for preventing escape of moisture along said shaft to the exterior of the reservoir.

28. In a machine for serving strips of adhesive tape, a frame or housing having opposite side walls providing a space between them for supporting the package or tape in position to be drawn upon, a reservoir adapted to be received and supported between said side walls, a rotatable moistener in said reservoir, a moisture feeding roll 41, and a yielding frame in said reservoir supporting said roll 41 in moisture feeding relation to said rotatable moistener.

29. In a machine for serving strips of adhesive tape, a frame or housing having opposite side walls providing a space between them for supporting the package or tape in position to be drawn upon, a reservoir adapted to be received and supported

between said side walls, a rotatable moistener in said reservoir, a moisture feeding roll 41, a yieldable frame for supporting said roll 41 in the reservoir, and means for detachably securing said frame to a wall of the reservoir.

30. In a machine for serving strips of adhesive tape, a frame or housing having opposite side walls providing a space between them for supporting a package of tape in position to be drawn upon, a reservoir adapted to be received and supported between said side walls, a main, rotatable moistener in said reservoir having a substantial portion thereof below the high

liquid level whereby normally moisture is received directly by said main moistener, an auxiliary, moisture feeding roll of smaller diameter than said main moistener and positioned in said reservoir below the latter, 20 and means in said reservoir supporting said auxiliary roll in position to transfer moisture to said main moistener by contact therewith thereby to supply the same with moisture when the liquid falls below the lowest 25 portion of said main moistener.

In testimony whereof, I have signed my name to this specification.

TREVOR RANDALL GAUTIER.
